UNITED STATES PATENT OFFICE.

CHARLES FABRICUS CARTY, OF WASHINGTON, NORTH CAROLINA.

TUBE-EXPANDER.

SPECIFICATION forming part of Letters Patent No. 743,146, dated November 3, 1903.

Application filed December 13, 1902. Serial No. 135,038. (No model.)

To all whom it may concern:

Be it known that I, CHARLES FABRICUS CARTY, a citizen of the United States, and a resident of Washington, in the county of Beaufort and State of North Carolina, have invented a new and Improved Tube-Expander, of which the following is a full, clear, and exact description.

This invention relates to a tube-expander, one of the leading features of which is the corrugation or roughening of the rollers, causing said rollers to make irregular and crossing indentations in the tube, thus facilitating the work of expanding the same.

15 The invention also relates to certain novel features of construction concerned with the other parts of the tube-expander, which enable the action of the rollers to be rendered more thoroughly effective.

20 This specification is an exact description of one example of my invention, while the claims define the actual scope thereof.

Reference is to be had to the accompanying drawings, forming a part of this specification, 25 in which similar characters of reference indicate corresponding parts in all the views.

Figure 1 is a side elevation of the invention. Fig. 2 is a longitudinal section thereof. Fig. 3 is a cross-section on the line 3-3 of Fig. 30 2. Fig. 4 is a cross-section on the line 4-4 of Fig. 2, and Figs. 5 to 10 are views illustrating various forms of roughened or irregular surfaces on the expanding-rollers.

25 *a* indicates the tubular body of the device, which is formed with a central cavity *a'* and three or more cavities *a''* for the rollers, these cavities *a''* extending radially outward from the central cavity *a'*. The body *a* has a shoulder *a''* thereon, and against this shoulder bears 40 a disk or plate *b*, carrying the lateral flanges *b'*, which are adapted to inclose the pipe in the usual manner.

Attached to the inner end of the body *a* is a tube *c*, which forms a continuation of the central passage *a'*, and in this passage *a'* and tube *c* is located the expander-spindle, which comprises an essentially triangular wedge-shaped portion *d* and a threaded portion *d'*. The threaded portion *d'* passes through the 45 outer end of the body *a* and carries a nut *e*, which has a tubular extension *e'* fitted in a corresponding cavity *a''* in the body *a* and

formed with an annular groove *e''*, in which is secured a key *e'*, this key holding the nut to turn freely on the body *a*, but preventing 55 longitudinal movement of the nut. It is clear that by turning the nut *e* the spindle *d, d'* may be moved longitudinally in the body *a* in either direction desired. The said spindle is kept from rotation by a key *f*, which is 60 fastened in the body *a* adjacent to its outer end and bears in either one of two grooves *d''*, formed in the threaded portion of the spindle. Two grooves are provided in order to permit the spindle to be held with its flat 65 faces or its corners against the roller-boxes, according to the preference of the user, and to change from one groove to the other the key *f* should of course be withdrawn, the spindle turned as desired, and then the key moved 70 back.

g indicates the roller-boxes, and *h* indicates the rollers. The boxes are of essentially rectangular form and have the roller-trunnions *h'* mounted to turn freely in the boxes *g*, so 75 that the outer portions of the peripheries of the rollers will be exposed.

i indicates pins or catch devices which are held in the body *a* and are pressed against the respective roller-boxes *g* by means of rubber cushions or other form of spring *i'*. The said boxes *g* are provided with recesses *g'* in their ends, in which recesses the rounded heads of the pins or spring-catches *i* are adapted to project, thus holding the boxes in place 85 and permitting the movement of the boxes outward under the action of the wedge or tapered portion *d* of the spindle and also permitting the complete removal of the roller-boxes when it is desired to change the form 90 of the rollers or to place cutters in the cavities *a''*, thus adapting the device to a tube-cutter.

The surfaces of the rollers *h* are corrugated, 95 roughened, reduced, or made irregular in any other way, so as to cause the rollers when working against the tube to form irregular indentations in the tube, thus making the work of expanding the tube easier. Figs. 5, 6, 7, and 8 show various forms of regular corrugations. Fig. 9 shows a pitted roller, and Fig. 10 shows a roller with broken corrugations. It is clear that these effects may be employed indefinitely without departing from the es- 100

sential principle of my invention. These roughened rollers make the work of expanding the tube much easier than with instruments where the rollers are of regular or smooth form.

The manner of using the invention will be apparent to persons skilled in this art, since it does not differ from the use of tube-expanders as heretofore constructed. By this means, however, the work of expanding the tube may be done much more easily and rapidly than heretofore.

Various changes in the form, proportions, and minor details of my invention may be resorted to at will without departing from the spirit and scope thereof. Hence I consider myself entitled to all such variations as may lie within the intent of my claims.

Having thus described my invention, I claim as new and desire to secure by Letters Patent—

1. A tube-expander, comprising a body, a roller mounted to turn freely against the tube and having a roughened surface, a box mounted to move in the body in which box the roller is mounted to turn, and a tapered spindle working against the box to move it.

2. A tube-expander, comprising a body, a box, a spring-pressed pin engaging the box movably to hold the same, a roller carried by the box, means for moving the box and roller, said spring-pressed pin comprising a pin provided with a rounding head engaging the box, and a cushion set back of said head and bearing between the same and the body.

3. A tube-expander, comprising a body, a roller mounted thereon, a spindle for operating the roller, means for moving the spindle, said spindle having two longitudinal grooves therein, and a key capable of bearing in either of said grooves.

4. A tube-expander, having a body, a plurality of rollers mounted thereon, said rollers being diversely corrugated so as to form crossing indentations in the tube, for the purpose 45 specified.

5. A tube-expander, comprising a body, a box engaged therewith, an expanding-tool mounted in the box, and a spring-pressed catch mounted in the body and slidably engaged with the box, for the purpose specified. 50

6. A tube-expander, comprising a body, a box engaged therewith, an expanding-tool carried by the box, said box having a groove in its outer surface, and a spring-pressed 55 catch bearing in said groove removably to hold the box and to allow it a limited movement within the extent of said groove.

7. A tube-expander, comprising a body, a roller mounted thereon, a tapered spindle for 60 operating the roller, means for moving the spindle longitudinally of the body, and a guide device capable of holding the spindle in either one of two radial positions without interfering with its longitudinal movement. 65

8. A tube-expander, comprising a body, a roller mounted thereon, a tapered spindle for operating the roller, means for moving the spindle longitudinally of the body, a guide device capable of holding the spindle in either 70 of two radial positions without interfering with its longitudinal movement, said device comprising a key on the body, and two keyways in the spindle with either of which said spindle is capable of engaging. 75

In testimony whereof I have signed my name to this specification in the presence of two subscribing witnesses.

CHARLES FABRICUS CARTY.
